UNITED STATES PATENT OFFICE.

ELMER L. FULLER, OF ARLINGTON, AND PERCY E. DE ROCHEMONT, OF MEDFORD,
MASSACHUSETTS.

SHOCK-ABSORBER.

1,297,827.

Specification of Letters Patent. Patented Mar. 18, 1919.

Application filed July 24, 1917. Serial No. 182,522.

To all whom it may concern:

Be it known that we, ELMER L. FULLER and PERCY E. DE ROCHEMONT, citizens of the United States, residing, respectively, at 5 Arlington, in the county of Middlesex and State of Massachusetts, and at Medford, in the county of Middlesex and State of Massachusetts, have invented new and useful Improvements in Shock-Absorbers, of which 10 the following is a specification.

The present invention relates to shock absorbers which are used upon motor cars to resist the throw of the car body under the influence of road inequalities.

15 Many types of shock absorbers have been devised to resist the throw of the car body under road inequalities, but all of these different types have developed serious faults in operation, and have not successfully accomplished the function for which they were 20 designed.

The object of the present invention is to produce a shock absorber which will operate to resist the throw of a car body under road 25 inequalities in a positive manner without the use of springs, fluid pressure devices or delicate parts liable to get out of order or require frequent attention, which will permit the use of a lighter and more flexible body 30 supporting spring than heretofore considered necessary and which will operate in an efficient manner to resist abnormal throw of the car body without liability of breaking the spring or racking the car.

35 To the accomplishment of this object, and such others as may hereinafter appear, the features of the present invention relate to certain devices, combinations and arrangements of parts fully described hereinafter 40 and then pointed out in the appended claims.

The various features of the present invention will be readily understood from an inspection of the accompanying drawings 45 illustrating the best form of the invention at present devised, in which,

Figure 1 is an elevation of the shock absorber positioned on a car body;

Fig. 2 is a plan;

50 Fig. 3 is a sectional plan;
Fig. 3^a is a detail illustrating the tool for adjusting the initial pressure on the disks shown in Figs. 5 and 6;

Fig. 4 is a sectional elevation on the line 4—4, Fig. 3, showing the split disk for receiving the end thrust of the oscillating shaft;

Fig. 5 is a sectional elevation on the line 5—5, Fig. 3, showing one of the disks carried by the housing;

Fig. 6 is a sectional elevation on the line 6—6, Fig. 3, showing one of the stationary disks carried by the oscillating shaft;

Fig. 7 is an elevation of the stationary cam disk;

Fig. 8 is an elevation of the cam disk on the oscillating shaft;

Fig. 9 is a detail in plan showing the engagement of the cam disks, and

Fig. 10 is a sectional plan of the cam 70 disks.

In the illustrated embodiment of the invention the shock absorber is mounted in a housing 1 which is secured by bolts 2 to the car body. The housing 1 is provided with 75 internal and external threads 3 and 4 upon which are threaded, respectively, a plate 5 and a cap 6. The plate 5 is provided with a step bearing for a headed shaft 7 which is oscillated in the bearing, responsive to the throw of the car body, through an arm 8 connected to the shaft and the axle of the car by any of the usual means found desirable or expedient. The end thrust of the shaft 7 is exerted on a split disk 9 (Fig. 4) 80 which loosely engages a groove 10, formed on the shaft 7, and which is held in a stationary position on the housing 1 by a series of teeth 11, formed on the disk, interlocked with a series of longitudinal grooves 12 85 formed on a portion of the interior of the housing 1.

In order to resist the oscillating movement of the shaft 7 responsive to the throw of the car body the shock absorber is provided with 95 a plurality of friction surfaces which move relatively while held together under pressure. These surfaces are formed upon an alternate series of disks 13 and 14 carried, respectively, by the shaft 7 and housing 1. 100 The disks 13 are provided with internal teeth 15 which are interlocked with a series of longitudinal grooves 16 formed on a portion of the shaft 7. The disks 14 are provided with external teeth 17 which are interlocked with the grooves 12 on the housing 1. 105

This method of mounting the disks on the shaft and housing is highly efficient as it facilitates the assembling of the disks in position and enables them to move relatively 5 under pressure with a minimum of liability of the disks working loose and thus becoming noisy.

The pressure between the disks 13 and 14 is initially regulated by a mechanism 10 presently to be described. During the operation of the car this initial pressure is automatically increased in a manner directly proportional to the throw of the car body under road inequalities. To this end the grooves 15 12 receive teeth 18 formed upon the periphery of a disk 19. The disk 19 carries an irregular cam surface 20 which engages a similar cam surface 21 on a disk 22 having internal teeth 23 thereon engaged with the 20 grooves 16 on the shaft 7. The disk 22 is pressed upon by a plug 24 adjustably carried by the cap 6. The cam surfaces 20 and 21 are so arranged that when the shaft 7 is oscillated under the influence of the 25 throw of the car body, the disks 13 and 14 will be wedged closer together thus increasing the pressure on the friction surfaces. The inclines on the cam surfaces 20 and 21 are designed to increase the pressure for 30 resisting the oscillation of the shaft 7, responsive to the throw of the car body, in a manner directly proportional to the said throw.

In order to regulate the initial pressure of 35 the friction disks, the plug 24 is provided with a series of teeth 25 which may be engaged by a pinion 26 on a shank 27 of a hand operated tool 28 (Fig. 3^a). During the use of the tool 28 the end of the shank 40 27 fits in a socket 29 formed in the cap 6. To retain the adjustable position of the plug 24 the cap 6 carries a dog 30 which is provided with teeth 31 for engagement with the teeth on the plug 24. The dog 30 is 45 removed to permit the insertion of the shank 27 in the socket 29 and is thereafter replaced to retain the adjusted position of the plug.

By means of the adjustable plug 24 the 50 shock absorber may be regulated for use on all kinds of cars. For instance, if the absorber is to be used on a truck or other heavy duty car, the plug will be adjusted to place an initial heavy pressure on the disks, 55 while if the absorber is to be used on a light pleasure car, the initial pressure will be reduced.

It will be noted that the oscillation of the 60 shaft 7 under the throw of the car body under road inequalities is resisted in both directions, that is, upon upward and downward movement of the car body beyond its normal operating position. It may be desirable to vary the time interval at which the

pressure on the disks is increased after the 65 car body is thrown under road inequalities. That is, it may be desirable to allow the disks to move relatively under the initial pressure for an interval of time before the pressure automatically increases when the 70 throw of the car body under road inequalities is upward and to immediately increase the pressure on the disks when the car body passes downwardly beyond the normal operating position. In order to permit this 75 differential action of the shock absorber, the disk 22 may be removed and then replaced with the cam surface 21 engaged with a different portion of the cam surface 20.

From the foregoing description of the 80 construction and mode of operation of the shock absorber it will be apparent that it is simple, compact and strong in construction without working parts liable to get out of order or cause annoyance by becoming noisy. 85 As the absorber resists the throw of the car body in both directions beyond the normal operating point it will be apparent that the shock absorber will operate equally well on either side or the rear of the car and consequently no special construction or marking is necessary to indicate rights and lefts or tops and bottoms.

It will be clear to those skilled in the art 90 and with the general objects of the present invention in view, that changes may be made in the details of structure, the described and illustrated embodiment thereof being intended as an exploitation of its underlying essentials, the features thereof being 100 definitely stated in their true scope in the claims herewith.

What is claimed as new, is:—

1. A shock absorber, having, in combination, an oscillating shaft responsive to the 105 throw of the car body under road inequalities; a set of disks comprising a plurality of non-rotatable disks and a plurality of friction disks on the shaft engaged with the other disks, said disks coöperating to 110 resist movement of the shaft responsive to the throw of the car body, a second set of disks comprising a non-rotatable disk and a disk on the shaft coöperating to press the 115 first set of disks together with a variable pressure during the oscillating movement of the shaft; and an adjustable plug bearing upon one of the disks of the second set for initially regulating the pressure on the disks of the first set.

2. A shock absorber, having, in combination, an oscillating shaft responsive to the throw of a car body having a grooved portion, a housing therefor provided with bearings for the shaft and with internal grooves 125 therein, a plurality of disks mounted to alternately engage the grooves in the shaft and housing and relatively movable in en-

gagement to resist the oscillating movement of the shaft, a second set of disks mounted to engage the grooves on the shaft and housing, respectively, a plug adjustable on the housing to engage one of the disks of the second set to regulate the initial pressure on the first set of disks, and a plurality of engaged cam surfaces on the second set of disks for wedging the first set of disks together during the oscillating movement of 10 the shaft.
